UNITED STATES PATENT OFFICE.

VALENTINE G. BAUER, OF BROOKLYN, NEW YORK.

SELF-ACTING AIR-INLET.

SPECIFICATION forming part of Letters Patent No. 721,853, dated March 3, 1903.

Application filed October 28, 1901. Renewed September 17, 1902. Serial No. 123,721. (No model.)

To all whom it may concern:

Be it known that I, VALENTINE G. BAUER, a citizen of the United States, and a resident of Brooklyn, in the county of Kings and State 5 of New York, have invented a certain new and useful Self-Acting Air-Inlet, of which the following is a specification.

My invention relates to automatic valves for admitting air to sewer-traps and for analogous purposes and constructed and arranged to be closed automatically, thus preventing the slightest escape or outcurrent from the pipe connected therewith, and to open whenever a vacuum-pressure takes place therein, 15 thereby securing an incurrent of air and ventilation of the said pipe and avoiding the retention of deadly gases in the plumbing-fixtures of a building; and it has for its object the provision of a device of the kind set forth 20 simple in construction, inexpensive to manufacture, and which operates automatically and efficiently in use.

To attain the desired end, this my invention consists in the construction, arrangement, and operation of parts herein set forth.

In order to enable my invention to be fully understood, I will proceed to explain the same by reference to the drawings which accompany and form a part of this specification, in 30 which—

Figure 1 represents a vertical cross-section of a self-acting air-inlet constructed according to my invention. Fig. 2 is a plan view of the same, showing a portion of the hood cut 35 away; and Fig. 3 is a view in section of another air-inlet constructed according to my invention.

Like letters of reference indicate like parts in all the views.

I have found it desirable to construct a self-acting air-inlet which may be set level or on a horizontal part of a fresh-air pipe or otherwise at will, the same being constructed and arranged to act equally well in any position 40 and to be attached to any house drain or soil pipe between the intercepting-trap and the connections to the building and also to be readily inspected or removed without injury, and I have therefore constructed according 45 to my invention an organization of the class described embodying the preferred construc-

tion of parts and their mutual relationship, combination, arrangement, and organization in a composite body or structure, as herein-after described.

Referring particularly to the drawings, A denotes the preferably circular sleeve or shell of my inlet constructed and arranged to fit and to be leaded and packed in a T of standard make (not shown) in the usual manner. 55 The upper part of the sleeve or shell A is ordinarily enlarged and is provided adjacent to the top thereof with a preferably enlarged or projecting portion A' and also with supporting devices, as three horizontal lugs a. A 60 ring or collar B, which sets on the top of the shell A, is also ordinarily provided with three horizontal lugs b, constructed and arranged to register with the lugs a and to be secured thereto, as by screws b'. The contacting faces 65 of the shell A and the collar B are preferably shouldered in order to hold the transverse plate C therebetween in an air-tight relation, which plate C may be constructed of any suitable material and is provided with a central 70 opening surrounded by a beveled edge C', forming a valve-seat. The collar B is also preferably provided with three vertical ribs or posts b², upon the tops of which rest screws d, which serve to support the hood E. 75

My valve consists, preferably, of a copper disk F of concavo-convex or dish shape and counterbalanced so as to rest against the valve-seat C', formed in the top of the plate C, although any other form of valve may be 80 substituted therefor.

My counterbalancing means consists of an eccentrically-mounted weight G and adjusting-screw g or a spring G², having adjusting-screw g². This counterbalancing means is 85 secured in an adjustable relation near the end of a rod f, which serves to support the valve F, and is provided with a transverse bar f², sustained by pointed screws h, located in the posts H, depending from the plate C. 90

It is manifest that various omissions of some particulars could be made without materially affecting the essential features of my invention or the operation of the remaining parts, and I do not, therefore, wish to be limited to the specific structural details of the organization herein set forth.

Obviously the elements of the structure described may be located at an angle to the plane in which they are shown. I accordingly use the words "horizontal," "vertical," 5 and the like in a relative sense.

In operation my counterbalance may be adjusted so that my sleeve or shell A may be held in a vertical, horizontal, or intermediate position, and the said valve will open and 10 close automatically in order to prevent the escape of sewer-gas, &c., and to secure when opened temporarily by a downtime of fresh air the proper ventilation of the plumbing system of the building.

15 My valve is very sensitive to internal pressure on account of its shape, being flexible or yielding on account of being constructed of thin metal, and also serves in connection with the beveled seat C' to form an air-tight 20 joint with very little pressure. By moving the eccentrically-mounted weight G around the rod f it is obvious that the same may be adjusted so as to hold the valve F against the seat C'.

25 As it is evident that many changes in the construction, form, proportion, and relative arrangement of parts might be resorted to without departing from the spirit and scope of my invention, I would have it understood 30 that I do not restrict myself to the particular construction and arrangement of parts shown and described, but that such changes and equivalents may be substituted therefor, and that

What I claim as my invention is—

1. In a fresh-air inlet, the combination with 35 a sleeve or shell having a flange provided interiorly with a shoulder, and a rim or collar located thereon and also provided interiorly with a shoulder, and provided with vertical 40 posts or ribs, and an intermediate transverse plate to engage said shoulders and provided with a beveled valve-seat, of a flexible or yielding thin-metal valve of concavo-convex or dish shape, and means for holding the 45 valve to the seat consisting of an eccentrically-mounted overbalancing device, and also of a hood supported by screws resting upon said posts.

2. In a fresh-air inlet, the combination with 50 a sleeve or shell, and with an interior transverse plate forming a valve-seat, of a valve of concavo-convex or dish shape, and means for holding the valve to the seat consisting of an eccentrically-mounted overbalancing de- 55 vice secured near the end of a rod supporting the valve from below, and provided with a transverse bar sustained by pointed screws located in posts depending from the said interior transverse plate.

In testimony of the foregoing specification I do hereby sign the same, in the city of New York, county and State of New York, this 18th day of October, A. D. 1901.

VALENTINE G. BAUER.
